UNITED STATES PATENT OFFICE.

ARTHUR HERMANN ROSING, OF PARIS, FRANCE.

SIGNAL FOR VEHICLES.

No. 827,265.

Specification of Letters Patent.

Patented July 31, 1906.

Application filed November 16, 1904. Serial No. 232,872.

To all whom it may concern:

Be it known that I, ARTHUR HERMANN ROSING, a subject of the King of England, residing at Paris, France, have invented new and useful Improvements in or Relating to Signals for Vehicles, of which the following is a specification.

This invention relates to a signal system for motor-cars, tram-cars, or other vehicles in which the application of centrifugal force transmitted by one of the wheels is employed to exhibit in a window or frame suitably arranged at the back of the car a suitable signal consisting, for instance, of the words "Stop," "Slacken," "Back" in order to notify drivers of vehicles at the back that they must stop, slow down, or back in order to avoid accidents, so that the driver is no longer required to make the usual signals.

In the accompanying drawings, by way of example, Figure 1 shows a plan view, partly in section, of part of the back of a vehicle, showing an application of the system. Fig. 2 is a front view of the signal-board. Fig. 3 is a section on line 3 3 of Fig. 2. Figs. 4 and 5 are detail views of parts of the apparatus.

To the back of the vehicle is secured a support 6, terminating in a sleeve 7, in which can freely turn the sleeve 8 of a ball-governor 9, the central shaft 10 of which can freely move in the inner sleeve 8 and is attached at its end, by means of a ball-joint 11, to a cord 12, passing over a guide-pulley 13 and preferably mounted in the interior of a tube 14. The other end of this cord is attached to one end of a pivoted lever 15, the other end of which is provided with a slot with which engages a stud 16, secured to the back of a board 17, which can freely move vertically along a slide 18 of a frame or casing 19, secured to the back of the car. The back of this frame is provided with a window or opening 20, below which another vertically-movable board 21 is guided.

On the sleeve 7 is concentrically mounted a ratchet-wheel 22, Fig. 5, with the teeth of which engages a pawl 23, pivoted to an arm 24, loosely mounted in a groove in the sleeve 7, to which arm is attached the end of a cord 25, guided between pulleys 26, 26, mounted on a bracket or support 27, secured to the sleeve 7. This bracket or support is provided at each of its ends with a tappet 28, serving to limit the movement of the arm 24. The cord 25 passes over a guide-pulley 29, preferably mounted in the interior of the

tube 14, over a second guide-pulley 30 and is attached with its end to one end of a pivoted lever 31, the other end of which carries the lower board 21, as shown in Fig. 2.

In the interior of the ratchet-wheel 22 is a circular groove 32, in which is placed a curved spring 33, one end of which is secured to the bottom of the said groove, while opposite to it the sleeve 8 has a prismatic or fluted cross-section, as shown in Fig. 5. To the sleeve 8 is keyed a grooved pulley 34 of comparatively small diameter, which can receive rotary motion from a larger pulley 35, secured to the hub of the corresponding driving-wheel 36.

When the car stops, the balls of the governor 9, which is not working, are brought close together and no traction is exercised by the governor on the cord 12. The board 17 is therefore in its lowest position behind the lowest board, and the word "Stop" with which it is provided appears at the window 20. As soon as the car starts the pulley 35 transmits to the pulley 34, to the sleeve 8, and to the balls of the governor a rotary motion, the result of which is that the balls of the latter move apart and traction is exercised on the cord 12, which swings the lever 15, and the board 17 rises until the car having reached its normal speed the board 17 is completely raised and no indication appears in the window 20. If the speed of the car begins to decrease, the balls of the governor 9 approach nearer to each other, the cord 12 is slackened, and the board 17 descends by gravity, bringing the word "Slacken" in front of the window 20. In the event of a complete stop the balls come still nearer together, and the board 17 sinks sufficiently low for the word "Stop" to appear at the window 20.

If the car is moving backward, the pulley 35 transmits to the pulley 34 a rotary movement in the opposite direction, and then the ratchet 22 acts on the pawl 23 and swings the arm 24, which exercises a pull on the cord 25, guided between the rollers 26. This traction results in the lever 31 being turned, raising the board 21, so that the word "Back" appears at the window or opening 20. If the backing continues, the sleeve 8 rotates while exercising friction on the spring 33 without carrying the ratchet 22, but in such manner that the friction is sufficient to hold the arm 24 inclined and the board 21 raised. If, therefore, the car slackens its speed, the word "Slacken" appears at the

window 20. If the car stops, the word "Stop" appears there, and if it travels backward, the word "Back" will appear. In any case the drivers of vehicles behind are thus warned without the driver of the car carrying the apparatus being obliged to make any signal or to trouble about vehicles behind him.

It is important that in spite of the vibrations of the car the board 17 should remain stationary. To that end a spring 37 is wound round the pin 38 of the lever 15, which engages with one of its ends in a hole in the bottom of the frame 19, which forms a support for it. One of the ends of this spring 37 enters a hole in the frame 19, and the other end engages in a hole in the lever 15, as shown in Fig. 4, so that owing to the interposition of the spring between the frame and the lever 20 the vibrations of the latter due to the vibrations of the car are suppressed or taken up.

At night-time the signals will be suitably illuminated, so that they may be visible.

What I claim as my invention, and desire 25 to secure by Letters Patent, is—

1. In a signal for vehicles, the combination with a centrifugal governor of means for operating the said governor from one of the wheels of the vehicle, of a frame arranged at 30 the back of the car and provided with a win-

dow or opening, a movable board in said frame carrying two words a second board also movable in the frame and carrying another word a lever attached to the first board and connected by a cord to the sleeve of the 35 governor, another lever operating the second board, a cord attached to this second lever, an arm attached to the cord and a ratchet-gear mounted frictionally on the sleeve of the governor, substantially as described. 40

2. In a signal for vehicles, the combination with a centrifugal governor, of a sleeve carrying the arms for the balls of the governor, a grooved pulley mounted on the said sleeve, a grooved pulley attached to one of the wheels of the vehicle, a frictionally-mounted pawl-gear on said sleeve an arm fixed on the pawl-gear, an indicator-board movable in the indicator-frame and means for transmitting the movement of the said arm to the said indicator-board, substantially as described. 45

In witness whereof I have hereunto signed my name, this 19th day of October, 1904, in the presence of two subscribing witnesses. 50 55

ARTHUR HERMANN ROSING.
